B. L. Agnew

UNITED STATES PATENT OFFICE.

B. L. AGNEW, OF INDIANA, PA., ASSIGNOR TO G. P. REED, OF SAME PLACE.

IMPROVEMENT IN PRESERVE-CANS.

Specification forming part of Letters Patent No. **25,863**, dated October 18, 1859.

To all whom it may concern:

Be it known that I, BENJAMIN L. AGNEW, of Indiana, in the county of Indiana and State of Pennsylvania, have invented a new and useful Improvement in Preserve-Cans; and I hereby declare that the following is a full and clear description thereof, reference being had to the accompanying drawings, and to the letters of reference marked thereon, making part of this specification.

The nature of my invention consists in a preserve-jar constructed with an inner rim or flange of less depth than the outer rim or flange, forming the mouth proper of the jar, whereby the V-groove between the two flanges or rims, and also the entire top of the stopper or cork, can be supplied with cement in a manner to render the jar perfectly air-tight, and also render impossible the detaching or breaking off the cement.

I am aware that many inventions have been essayed in which melted wax and rosin or some similar mixture for pouring upon and covering the mouth of the jar have been used; also, that caps requiring cement to seal them to the top of the jar have been in common use; but in every instance, so far as I am aware, the above-named devices have proved ineffectual, and the cost attending their construction renders their introduction very slow.

The jar I propose may be manufactured of stoneware, tin, glass, or queensware formed

as herein described, namely: The mouth of the jar, being made of any convenient size, is formed with an annular V-shaped cavity or receptacle, B, between the flaring portion of the neck E and a flange, C. This flange C is made with and forms part of the jar. The V-shaped cavity is formed to retain the cement in the mouth of the jar.

As shown clearly in Figure 2, A is a conical-shaped stopper, formed to fit closely within the rim or flange C, and, when fitted to its place for use, is formed to project slightly above the rim C, as represented. Fruit being prepared in the ordinary manner and placed within the jar, the stopper A will be fitted closely in its place, and cement will be poured into the cavity B until the top of the stopper A is fully covered, thereby rendering the jar perfectly air-tight.

What I claim as my invention, and desire to secure by Letters Patent, is—

The combination, in a preserve-jar, of a deep outer flange or rim, E, with a shallow inner flange, B, in the manner and for the purpose herein described.

In testimony of which invention I have hereunto set my hand.

B. L. AGNEW.
